UNITED STATES PATENT OFFICE.

MICHAEL HENRY SULLIVAN, OF POUGHKEEPSIE, NEW YORK.

PISTON AND PISTON RING.

Application filed October 31, 1921. Serial No. 511,910.

To all whom it may concern:

Be it known that I, MICHAEL H. SULLIVAN, a citizen of the United States, residing at Poughkeepsie, in the county of Dutchess and State of New York, have invented certain new and useful Improvements in Pistons and Piston Rings; and I do declare the following to be a full, clear, and exact description of the invention, such as will enable others skilled in the art to which it appertains, to make and use the same.

My invention relates to improvements in pistons and piston rings and has for its principal object to improve upon the construction disclosed in my United States application, Serial No. 475,543, filed on or about June 6th, 1921. When installing the improved rings upon comparatively small pistons, it was found impracticable to groove the ring sections in the manner disclosed by the application just referred to, due to the fact that the relatively narrow rings would thus be excessively weakened. It is the aim of the present invention therefore to provide a construction which will be equally as efficient as that previously contemplated, without the necessity of grooving the rings, it being merely necessary to provide the meeting ends of the ring sections with communicating recesses which receive a portion of the sealing block or blocks.

With the foregoing in view, the invention resides in the novel subject matter herein-after described and claimed, the descriptive matter being supplemented by the accompanying drawing.

Figure 1 is a side elevation showing a piston equipped with the improved features.

Figure 2 is a horizontal sectional view as indicated by line 2-2 of Fig. 1.

Figure 3 is a vertical sectional view on line 3-3 of Fig. 1.

Figure 4 is a perspective view of one of the sealing blocks.

In the drawings above briefly described, the numeral 1 designates a piston provided with a suitable number of piston ring grooves. I have shown three of these grooves provided with common snap-rings 2 and a fourth groove 3 with which the improved features of construction are associated, said groove 3 being located at the head of the piston.

At diametrically opposite points, I have shown one side wall of the groove 3 provided

with shallow circumferentially elongated recesses 4 which extend throughout the depth of the grooves. The ring which is received in the groove 3 is formed, as here shown, of two semi-circular sections 5 forced radially outward by a single coil spring 6. The meeting ends of the ring sections 5 are formed with communicating recesses 7 which open through the periphery of the ring and through the side of the latter facing the recesses 4, said recesses 6 preferably extending throughout about one-half of the axial width of the piston ring and throughout slightly more than half the radial width of the ring. The inner walls 7' of the recesses 7 constitute shoulders to bear against a pair of sealing blocks 8. Two of these blocks are employed, each block occupying one of the recesses 4 and the adjacent recesses 7, the proportions being such that while the blocks 8 are snugly received in the recesses, they may move therein sufficiently to cause the shoulders 7' to thrust the curved peripheries of said blocks into pressure-tight contact with the cylinder wall. In the form of the invention herein shown, the portion of each sealing block 8 occupying a recess 4, is considerably longer and wider than the portion which fills the recesses 7 and I have also shown said first named portion provided with a transverse rib 9 received in a similarly shaped groove 10 in the bottom of the recess 4. It will be understood however that these details need not be followed too closely, as various modifications may be resorted within the scope of the invention as claimed.

I prefer to use the improved sealing means with a two-part ring in which both sections are forced radially outward by a single spring such as 6 acting on the centers of said sections, but it will be understood that said sealing means might also be employed in connection with other types of rings. When the spring 6 is used, it is preferably housed in a tube 11 extending diametrically across the interior of the piston. A pair of suitably shaped heads 12 are slidably received in the ends of this tube and by suitable pins or the like 13 are connected with the ring sections 5 so as to prevent traveling of said sections in the ring groove 3. The inner ends of the heads 12 are provided with necks 14 around which the ends of the spring 6 are positioned.

Regardless of the exact manner in which

the ring is opened by spring action, the sealing blocks will be highly efficient to prevent the escape of pressure and the leakage of oil. As any wear of the ring takes place and it 5 automatically moves outward to continually hug the cylinder wall, the contacting surfaces of the shoulders 7' and the sealing blocks 8 serve to automatically force said sealing blocks outwardly to the proper extent, so that they also will remain in fluid-tight contact with the wall of the cylinder. The construction shown has been installed on a number of pistons and used with great 10 advantage, and on account of the known efficiency of the details disclosed, they are 15 by preference followed. As above stated however it is to be understood that within the scope of the invention as claimed, numerous minor changes may be made.

20 I claim:—

1. A piston having a ring groove provided with a circumferentially elongated shallow recess in one of its side walls, a spring-opened ring in said groove having meeting 25 ends disposed at said recess, said ends being provided with communicating recesses opening through their peripheries and through the side of the ring facing the recess of the piston, and an elongated sealing block 30 snugly yet movably received in said recesses

of the piston and ring and having a curved periphery coincident with the ring curvature, the ends of said ring having shoulders bearing against the inner side of said sealing block to hold the same in cylinder-engaging 35 position.

2. A piston having a ring groove provided in one side wall with a pair of diametrically opposed shallow recesses elongated circumferentially, a ring in said groove formed of 40 two semi-circular sections whose ends meet at said recesses, said ends being provided with communicating recesses opening through their peripheries and through the side of the ring facing said recesses of the piston, a 45 spring extending diametrically across the piston and acting on the centers of said ring sections to force them against the cylinder wall, and a pair of elongated sealing blocks snugly yet movably received in said recesses of the 50 ring and piston and having curved peripheries coincident with the ring curvature, said ring sections having shoulders bearing against the inner sides of said sealing blocks to hold the latter in cylinder-engaging 55 position.

In testimony whereof I have hereunto set my hand.

MICHAEL HENRY SULLIVAN.
